H. W. KELLY.

TORPEDO.

APPLICATION FILED JUNE 27, 1914.

1,124,748.

Patented Jan. 12, 1915.

UNITED STATES PATENT OFFICE.

HUGH WILLIAMSON KELLY, OF TRENTON, NEW JERSEY, ASSIGNOR OF ONE-HALF TO
AUBREY LOVE, OF NEW YORK, N. Y.

TORPEDO.

1,124,748.

Specification of Letters Patent.

Patented Jan. 12, 1915.

Application filed June 27, 1914. Serial No. 847,643.

To all whom it may concern:

Be it known that I, HUGH WILLIAMSON KELLY, of Trenton, in the county of Mercer, and in the State of New Jersey, have invented a certain new and useful Improvement in Torpedoes, and do hereby declare that the following is a full, clear, and exact description thereof.

My invention relates particularly to torpedoes designed for use on railway tracks as signals, although it is applicable for use in other similar ways.

The object of my invention is to provide a torpedo which is arranged so as to prevent flying parts, and a further object of my invention is to provide a torpedo of great efficiency at a minimum cost and which may be made with a minimum amount of labor.

A further object of my invention is to provide a torpedo in which a bendable strap or clamping device is provided for securing a torpedo to a rail, but in which there is also means provided for clamping the torpedo to the rail through the agency of the strap or other clamping means, this being effected by using with the strap or clamping means a material having a frictioned surface which will bind the severed or fractured parts of the strap or clamping means together, and which will also retain them in the desired form to cause the clamping means to secure the torpedo to the rail after the severance or fracture of the strap or clamping means.

Another object of my invention is to provide a construction in which the outer surface of the torpedo is of such a nature that it will not slip along the rail, and in which additional non-slipping material may be readily applied thereto when desired.

A torpedo made in accordance with my invention is provided in general with an explosive body contained within any suitable container and adapted to be attached to a rail by a strap or any suitable clamping means, with which there is provided a frictioned material designed to bind the strap or clamping means together in its several parts, as well as to bind the same to the body of explosive both before and after the strap or clamping means has become severed or fractured in any of its parts. The frictioned material in question is also preferably of such a nature that it is adapt-

ed to confine the various parts of the torpedo in such a manner as to exert a restraining influence upon the flying of any of the solid parts of the torpedo when the explosion takes place and in case they should fly, to prevent the solid parts of lead or other material from doing as much damage as results from the use of uncovered fiber or metal parts. Furthermore, the frictioned material is preferably of such a nature that sand or any other agent designed to prevent slipping may be readily applied to the exterior of the torpedo.

While my invention is capable of embodiment in many different forms, for the purpose of illustration I have shown only certain forms thereof, in the accompanying drawings, in which—

Figure 1 is a perspective view of one modification of my invention; Fig. 2 is a similar view of another modification of my invention; Fig. 3 is a similar view of still another modification of my invention; Fig. 4 is a perspective view of still another modification thereof; and Fig. 5 is a cross-section of the torpedo shown in Fig. 1.

In the form of my invention shown in Fig. 1, I have provided an outer annular casing of any desired fabric as, for example, of duck, canvas, cheesecloth, calico, rubber, asbestos, etc., which may be frictioned on both surfaces; that is to say, it may be provided with sticky rubber or adhesive coatings 1^a and 1^b on the inside and outside, respectively. This casing incloses a body of explosive 2 and a strap 3 which may be made of any suitable material, such, for example, as lead, which is adapted to hold its shape when formed around the rail to which the torpedo is to be attached. The body of explosive may be incased in a separate wrapping 4 of any desired character, although this wrapping may be omitted when found unnecessary for maintaining the body of explosive 2 in position.

The modification shown in Fig. 2 is constructed in the same manner as the modification shown in Fig. 1, except that instead of using an annular body of fabric, the body of material is wrapped in a spiral roll of fabric 5.

In the modification shown in Fig. 3, the construction is the same as shown in Fig. 1, except that in this instance, instead of using

a strap 3 such as that shown in Fig. 1, there is provided a lead tube 6 containing the body of explosive 2.

In the modification shown in Fig. 4, the construction is the same as in Fig. 3, except that a lead tube 7 is provided which incloses a tubular fabric 8 which may be rubberized or provided with an adhesive coating on both sides thereof, but which may instead be provided only with an outside adhesive surface so as to cause the same to tightly adhere to the inclosing tube 7.

Furthermore, if desired at any time, a quantity of sand or other frictioning material 9 may be applied to the outer sticky or adhesive surface of the torpedo before being applied to the rail, so as to further prevent any slipping of the torpedo on the rail, as shown in Fig. 5.

20 A torpedo constructed in accordance with my invention will hold the various parts of the torpedo tightly together. That is to say, the frictioned fabric will hold the various parts of the strap or metal tube together 25 even when parts thereof become severed and will also hold the same to the body of explosive under similar circumstances. In other words, when the ends of the strap or metal tube have become fractured or severed, owing to the continual bending and rubbing to which the strap or tube is subjected in actual use of trainmen in carrying the torpedoes about preparatory to application to the rails, the frictioned fabric will 30 tightly bind the ends of the strap or metal tube to the remainder of the torpedo, and in such a manner that when the torpedo is applied to the rail, the torpedo will be held in place, notwithstanding the fracture or 35 severance of the ends of the strap or lead tube. This is evident from the fact that even when the ends of the strap or lead tube have become severed, when the ends of the strap or lead tube are bent over the sides of 40 the rail, the change in form of the adjacent 45 severed portions of the strap or tube will

be retained and, as a consequence, the torpedo will be held in place notwithstanding the severance or fracture of the ends of the strap or lead tube. With a construction of this kind, it therefore becomes practically impossible to damage the torpedo in operation in such a manner as to prevent its being secured to a rail for detonation. Furthermore, in a torpedo constructed in this manner, water and moisture are entirely excluded from the torpedo, so that the explosive composition therein cannot be damaged by the same. The use of woven fabric, furthermore, produces a louder detonation. 50 55 60

I am aware that tubular torpedoes have been previously constructed, but my invention relates to other features present in the construction described hereinabove.

While I have described my invention above in detail, I wish it to be understood that many changes may be made therein within the scope of the claims without departing from the spirit of my invention. 65 70

I claim:

1. A torpedo comprising a bendable stiffening member and a frictioned fabric having its inner surface frictioned and inclosing the bendable ends of the bendable stiffening member. 75

2. A torpedo comprising a bendable stiffening member and a frictioned fabric having its outside frictioned and inclosing the bendable ends of the bendable stiffening member. 80

3. A torpedo comprising a bendable stiffening member and a frictioned fabric having its inner surface frictioned and inclosing the bendable stiffening member and having its outside frictioned. 85

In testimony that I claim the foregoing I have hereunto set my hand.

HUGH WILLIAMSON KELLY.
